CONVEYER COUNTER

Eugene E. Flesner and John Lynch, Chicago, Ill.,
assignors to Jewel Tea Company, Inc., Chicago,
Ill., a corporation of New York

Application April 20, 1951, Serial No. 221,994

5 Claims. (Cl. 235—98)

1

This invention relates to a conveyor counter and more particularly to a counter assembly readily attached to conveyors of conventional construction to automatically register the number of shipping cartons conveyed.

To check the material or goods in a truck-load or a railroad car-load, the usual procedure is for the persons unloading or loading the truck or car to observe and count the number of shipping containers or cartons as they are unloaded or loaded and check the total number against the invoice. Since the total number of shipping containers or cartons in a truck load or car load may run into the hundreds, it is readily apparent that errors are likely to occur with this procedure. Such errors, of course, will result in a considerable waste of time since a recount is necessary when an error occurs.

It is an object of this invention to provide a counting assembly for ready attachment to conveyors of various types to automatically register the number of shipping cartons conveyed so that counting by observation or physical checking will not be necessary and so that errors and waste of time will be obviated.

According to this invention, a counting assembly is mounted on a conveyor of a conventional type having a plurality of parallel axles in an inclined plane, each axle having a plurality of carton supporting and guiding rollers rotatably disposed thereon. The counting assembly includes a pair of support plates adapted to extend over two adjacent axles, a connector plate extending between the support plates and affixed thereto, a register supported on the connector plate and having an actuating crank arm, and a lever pivotally secured to the rear end portion of one of the support plates and extending over the crank arm in a manner such that cartons moving on the rollers will engage and push the lever downwardly which, in turn, will move the crank arm downwardly to actuate the register. The support plates are so formed that longitudinal movement on the conveyor is prevented but can be readily removed from the conveyor and installed on another conveyor of similar construction.

The construction also features a curved lever arm so related to the crank arm that a minimum force is required to actuate the register so that the movement of the shipping containers will not be impeded, the curved lever arm also allowing actuation of the register by cartons moving in either direction on the conveyor.

Another object of this invention, accordingly, is to provide a counter assembly adapted for different conveyor line constructions.

2

A further object of this invention is to provide a counter assembly so constructed as to be readily lifted off a conveyor and, at the same time to stay in place regardless of vibration of the conveyor.

5 Still another object of this invention is to provide a counter assembly which is simple, compact and easily and economically manufacturable.

Other objects, features and advantages of the present invention will become more fully apparent from the following detailed description taken in conjunction with the accompanying drawings which illustrate a preferred embodiment and in which:

Figure 1 illustrates a conveyor with the counting assembly of the present invention mounted thereon, the conveyor being illustrated in operative position for conveying shipping containers from a truck to a loading platform;

Figure 2 is a top plan view of a portion of the conveyor of Figure 1 with the counting assembly applied thereto; and

Figure 3 is a sectional view, on an enlarged scale, taken substantially along line III—III of Figure 2, so that it is a side view of the counter assembly.

Referring to the drawings, Figure 1 shows a conveyor generally designated by reference numeral 10 disposed in an inclined position between the rear end of a truck 11 and a loading platform 12. Boxes, cartons or shipping containers placed on the truck end of the conveyor will move down the conveyor to the loading platform 12 by the action of gravity thereon. A shipping carton 13 is illustrated in an intermediate position on the conveyor. A counter assembly generally designated by reference numeral 14 is mounted on the conveyor to register the number of boxes passing thereover.

Figures 2 and 3 illustrate the construction of the conveyor and the counting assembly in detail. Referring thereto, the conveyor includes a pair of side frame members 16 and 17 having a plurality of axles or rods secured therebetween. Figure 2 illustrates four of the axles which are designated by the reference numerals 18, 19, 20 and 21. Rotatably disposed on each of the axles are a plurality of rollers 22 adapted to support and guide boxes moving on the conveyor. The provision of the rollers, of course, reduces frictional retardation of the containers moving down the conveyor.

The counter assembly includes a pair of support plates 24 adapted to extend over adjacent axles of the conveyor 10, such as axles 19 and 20, as illustrated. A connector plate 25 extends between the support plate 24 and is affixed to an

intermediate portion 24a of each of the support plates preferably by welding. Each of the support plates 24 is formed to extend, from the forward end of the intermediate portion 24a, successively upwardly adjacent the rear side of the axle 20, forwardly over the axle and downwardly adjacent the front side of the axle 20, and, from the rear end of the intermediate portion 24a, successively upwardly, rearwardly over the axle 19 and downwardly adjacent the rear side of the axle 19, as best illustrated in Figure 3.

It will be noted that longitudinal movement of the counter assembly on the conveyor is thus prevented and that the assembly can be readily lifted from the conveyor when desired. It will also be apparent that the axles 19 and 20 illustrated could be considerably closer together without affecting the mounting of the counter assembly thereon since the engagement of the portion of the support plate 24 with the axle 20 is sufficient to prevent longitudinal movement on the conveyor. Thus the assembly can be mounted on conveyors having various axle spacings.

A register or standard counting mechanism 26 is secured to the connector plate 25 by screws 27. This register 26 is of the conventional type and has an actuating shaft 28 to which an arm 29 is secured. The shaft 28 is spring biased by means in the register (not shown) to a position in which the arm 29 extends upwardly and forwardly as illustrated full lines in Figure 3. Movement of the arm 29 against the spring bias from the full line position to the dotted line position will actuate the register so that it will indicate a number one digit higher. The register has visible indicating means in the top side thereof which shows the total number of times the arm 29 has been actuated and is preferably provided with means for resetting the indicating means to zero.

To actuate the arm 29, a lever 30 is pivoted to the rear end portion of one of the support plates 24 and extends forwardly over the arm 29. Movement of the lever 30 downwardly about its pivotal axis from the full line position to the dotted line position, Figure 3, will cam the arm 29 downwardly about its pivotal axis to actuate the register 26. To reduce friction between the arm 29 and the lever 30 the arm 29 preferably has a roller 31 rotatably disposed on the outer end thereof and engaging the lower surface of lever 30. The pivotal connection between the lever 30 and the support plate 24 preferably is provided by a simple hook-and-eye arrangement including a bracket 32 affixed to the plate 24, as by welding, the bracket having a slot through which a hooked terminal end portion 30a of the lever 30 extends.

It will be apparent that movement of a carton 13 downwardly on the conveyor (to the right as illustrated in Figure 3) will cam the lever 30 downward about its pivotal connection to the support plate 24 and the lever 30 will, in turn, cam the arm 29 downwardly to actuate the register 26.

The lever 30 is preferably formed in a smooth curve with its outer end extending downwardly below the level of the top sides of the rollers, as illustrated in Figure 3. With this provision, the lever may be moved downwardly, and the register actuated, by cartons moving on the conveyor in either direction. The curvature of the lever also reduces the maximum instantaneous force required for actuation and hence reduces resistance to movement of containers on the conveyor. Although the assembly is preferably disposed so as

to be actuated with cartons moving in the direction illustrated, it will be apparent that an inadvertent placing of the assembly in a reverse position will not make it inoperable.

There is thus provided a conveyor counter which eliminates the necessity of mental counting to check invoices, is easily and economically manufacturable, is readily moved from one conveyor to another, may be operated in reverse positions, is reliable in operation and will stay in place regardless of vibrations of the conveyor.

It will be apparent that modifications and variations may be effected without departing from the spirit and scope of the novel concepts of the present invention.

We claim as our invention:

1. A counter for a conveyor having a plurality of parallel axles in an inclined plane, each axle having a plurality of shipping carton supporting and guide rollers rotatably disposed thereon; comprising; a pair of support plates adapted to extend over a first axle of the conveyor and over a second axle rearwardly spaced from the first axle; a connector plate extending between the support plates and affixed at each end to an intermediate portion of one of the support plates; each support plate being constructed and arranged to extend, from the forward end of the intermediate portion thereof successively upwardly adjacent the rear side of the first axle, forwardly over the top side of the first axle and downwardly adjacent the front side of the first axle and to extend, from the rear end of the intermediate portion, successively upwardly, rearwardly over the second axle and downwardly adjacent the rear side of the second axle; a register affixed to the connector plate and having an actuating arm pivoted on an axis generally parallel to the axles; the actuating arm being resiliently urged to an upwardly inclined position and being movable downwardly to actuate the register; and a lever pivoted to a rear portion of one of the bracket plates and extending over the register actuating arm in camming engagement therewith so that a carton moving forwardly on the conveyor will cam the lever downwardly to cam the arm downwardly to actuate the register.

2. In a conveyor having a plurality of parallel axles disposed in an inclined plane and a plurality of carton supporting and guiding rollers mounted on each axle, a carton counter mounted on a pair of adjacent axles and including a register having an actuating arm extending above a plane tangential to the upper portions of the rollers, and a lever pivoted from a rear portion of the counter and extending over the register actuating arm, cartons moving down the conveyor thereby camming the lever downwardly to operate the register actuating arm.

3. In a conveyor having a plurality of parallel axles disposed in an inclined plane and a plurality of carton supporting and guiding rollers mounted on each axle, a carton counter mounted on a pair of adjacent axles and including a register having an actuating arm extending above a plane tangential to the upper portions of the rollers, and a lever pivoted from a rear portion of the counter and extending over the register actuating arm, cartons moving down the conveyor thereby camming the lever downwardly to operate the register actuating arm, the outer end portion of the lever being curved downwardly and extending below said plane so that the lever and the regis-

ter may be actuated by cartons moving in either direction on the conveyor.

4. In a conveyor having a frame, a plurality of longitudinally spaced parallel axles carried by the frame and a plurality of laterally spaced rollers mounted on each axle, a counter for articles conveyed by said conveyor comprising a pair of spaced support members arranged to straddle at least one roller on each of two adjacent axles on said conveyor and to extend over said adjacent axles, said support members having end portions shaped to receive said axles for retaining the counter in position on the axles, means securing said support members in spaced relation, a register mounted on said means, and a register actuator rockably supported on said counter and resiliently urged to a position with a part thereof in the path of articles moving on said conveyor to be actuated by said articles as they pass through on said rollers. 15

5. In a counter for a conveyor including a pair of longitudinal frame members, a plurality of longitudinally spaced parallel axles carried between the frame members and a plurality of laterally spaced rollers on each axle, a support member arranged to extend longitudinally over a pair of adjacent axles intermediate the frame members and having end portions shaped to receive the adjacent axles for retaining the counter in position thereon, a register supported by said 20 30

support member intermediate said end portions thereof so as to be disposed between the pair of adjacent axles, and a register actuator resiliently urged to a position with a part thereof in the path of articles moving on the conveyor to be actuated by such articles as they pass through on the rollers.

EUGENE E. FLESNER.
